UNITED STATES PATENT OFFICE.

GEORGE A. HALTER, OF LAKEWOOD, OHIO, ASSIGNOR TO THE HALTER METAL PRODUCTS COMPANY, OF CLEVELAND, OHIO, A CORPORATION OF OHIO.

DESIGN FOR A HANGAR FOR TOY AEROPLANES.

Application filed February 23, 1928. Serial No. 25,552. Term of patent 14 years.

To all whom it may concern:

Be it known that I, GEORGE A. HALTER, a citizen of the United States, residing at Lakewood, in the county of Cuyahoga and State of Ohio, have invented a new, original, and ornamental Design for Hangars for Toy Aeroplanes, of which the following is a specification, reference being had to the accompanying drawing, forming part thereof.

In the drawing, Fig. 1 is a perspective view of a hangar for toy aeroplanes showing my new design; Fig. 2 is a front elevation; and Fig. 3 is a side elevation.

I claim:

The ornamental design for a hangar for toy aeroplanes, as shown.

GEORGE A. HALTER.
